(57) **CLAIM**

The ornamental design for a mobile communications device cover, as shown and described.

DESCRIPTION

FIG. 1 is a perspective view taken from the top, front, and left side of the mobile communications device cover of the present design.

FIG. 2 is a perspective view taken from the top, rear, and left side of the mobile communications device cover of FIG. 1

FIG. 3 is a front elevation view of the mobile communications device cover of FIG. 1.

FIG. 4 is a rear elevation view of the mobile communications device cover of FIG. 1.

FIG. 5 is a right side elevation view of the mobile communications device cover of FIG. 1

FIG. 6 is a left side elevation view of the mobile communications device cover of FIG. 1

FIG. 7 is a top plan view of the mobile communications device cover of FIG. 1; and,

FIG. 8 is a bottom plan view of the mobile communications device cover of FIG. 1.

The broken lines in FIGS. 1–4 and 8 depict environmental subject matter that forms no part of the claimed design.

1 Claim, 6 Drawing Sheets
